Primary Examiner — Catherine Ho

(57) **CLAIM**

The ornamental design for a feather flag sign as shown and described.

DESCRIPTION

FIG. 1 is a top perspective view of a feather flag sign, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detailed view of encircled area 9 in FIG. 1;

FIG. 10 is an enlarged detailed view of encircled area 10 in FIG. 2; and,

FIG. 11 is an enlarged detailed view of encircled area 11 in FIG. 2.

The dash-dash broken lines in the drawings depict portions of the feather flag sign that form no part of the claimed design. The dot-dash broken lines illustrate the border of enlarged detailed views and form no part of the claimed design.

1 Claim, 11 Drawing Sheets
